UNITED STATES PATENT OFFICE.

DAVID W. THOMPSON, OF CHICAGO, ILLINOIS.

TEMPERATURE-REGULATING APPARATUS.

SPECIFICATION forming part of Letters Patent No. 415,007, dated November 12, 1889.

Application filed October 4, 1887. Serial No. 251,386. (No model.)

To all whom it may concern:

Be it known that I, DAVID W. THOMPSON, of Chicago, in the county of Cook and State of Illinois, have invented certain new and useful Improvements in Temperature-Regulating Apparatus; and I do hereby declare that the following is a full, clear, and exact description thereof, reference being had to the accompanying drawings, and to the letters of reference marked thereon, which form a part of this specification.

This invention relates to improved temperature-regulating apparatus of that class embracing a valve or damper the opening or closing of which affects the temperature of a room or apartment, a motor actuating the said valve or damper, a thermostat, and electrical connections between the thermostat and the motor, whereby the latter is controlled from the former.

The invention consists in the matters hereinafter described, and pointed out in the appended claims.

In the accompanying drawings, illustrating my invention, Figure 1 illustrates an apparatus embracing the several novel features comprising the invention, the valve or damper being shown as applied to an auxiliary air-inlet pipe connected with the smoke-pipe of a stove or furnace. Fig. 2 is a section through the said pipe and the motor-case, illustrating features of construction in the motor and in the damper. Fig. 3 is a face view of the motor with the cover of the case removed. Fig. 4 is a sectional view of the case containing the thermostat. Fig. 5 is an enlarged detail side view of the pivoted armature and the part of the magnet adjacent thereto. Fig. 6 is a perspective view of the armature detached from its supporting-pivot. Fig. 7 is an enlarged face view of the motor shown in Fig. 2. Fig. 8 is an enlarged plan view of the same.

As illustrated in the said drawings, A indicates, as a whole, the thermostat and its case; B, the battery; C, the motor; D, the valve, which is actuated by the motor; E, the pipe in which the valve is placed.

In the particular construction illustrated the pipe E is connected with the smoke-pipe F of a stove F', the said pipe E being open at its lower end, so that when the damper D is

open air from the apartment may enter the smoke-pipe, and thus decrease or prevent the passage of air through the draft-apertures of the stove. The motor C is provided with a shaft C', which extends through the pipe E and supports the valve D, which, in this instance, is a simple disk or butterfly valve. The said motor consists of an ordinary clock-work driven by coiled actuating-springs C² C², and provided with a regulating-fan c. Upon the shaft C' of the motor is mounted a commutator C³, consisting of a cylindric block of metal provided with insulating blocks or sections c' c' c² c². The insulating-sections c' c' are arranged diametrically opposite each other, while the insulating-sections c² c² are arranged diametrically opposite each other at points intermediate to the sections c' c', the sections c' c' and c² c² being located at opposite sides of a central line drawn around the cylindric surface of the commutator in the manner shown.

G' G' are spring-arms or brushes attached to the frame of the motor and resting at their free ends upon the commutator C³. The brush G acts upon the insulating-sections c' c', while the brush G' acts upon the insulating-sections c² c².

The brushes G G' are herein shown as attached, respectively, to separate insulating-posts G² G³, attached to the frame of the motor. The brushes, as herein shown, consist of strips of metal or wire provided with double bends g g', forming parts g² g³, which are generally at right angles to the end portions of the brushes. The presence of the said transverse parts obviously enables the brushes to be lengthened or shortened by bending said transverse parts or the curved portions of the brushes connecting them, thereby enabling the parts of the brushes in contact with the distributor to be accurately adjusted with relation to said distributor.

The said commutator C is constructed and operates generally in the same manner as do other similar commutators to complete an electric circuit through one or the other of the brushes G G' and a conductor having electrical connection with the metal body of the commutator.

H is an electro-magnet mounted upon the frame of the motor, and H' an armature for

said magnet. Said armature stands vertically and is pivoted at its lower end upon a pivot-rod h . The armature is also provided with a rigid arm H^2 , having at its end a detent or hook h' , constructed to engage the regulating-fan c of the motor at the time the armature is free from the magnet.

H^3 is another rigid arm attached to the armature and extending outwardly over a stationary part or rod c^3 of the motor, which rod forms a stop to limit the downward movement of the said arm H^3 and of the detent-arm H^2 . In this construction of the parts the weight of the armature, in connection with the weight of the arms H^2 and H^3 , is relied upon to hold the armature free from the magnet at the time the current is not passing through the same and to cause the engagement of the detent h with the regulating-fan. It will of course be understood, however, that a single arm may be employed in place of the two arms shown, and that a stop for limiting the backward movement of the armature and the downward movement of the detent may be otherwise located than as shown. It will also be understood that the said detent may be arranged to engage a revolving part of the clock-work other than the regulating-fan.

In motor-controlling devices of the kind above described as heretofore made the armature is held or drawn away from the pole of the magnet by means of a spiral or other spring. An adjusting device for the spring is required in order to enable the tension of the same to be accurately adjusted, and by reason of changes in the spring itself and liability of shifting the screw with which the spring is connected and other reasons it becomes necessary to occasionally adjust the spring to produce perfect action of the device. By employing the arm H^3 , attached to the armature and extending outwardly therefrom in such manner that its weight will swing the armature away from the pole of the magnet, I am enabled to dispense with the spring, thereby obtaining a more simple and cheap construction, while at the same time obtaining a uniform action without possibility of the devices getting out of adjustment in use.

By reason of the advantages obtained by the construction in the motor in the particular above described this novel construction of the armature is herein claimed as a part of my invention.

A conductor i extends from the electro-magnet H to the frame of the clock-work, and has electrical connection through said frame, the shaft C' , and the metal body of the distributor C^3 with one or the other of the brushes $G G'$.

I is another conductor leading from the coil of the electro-magnet to the battery B . I' is a conductor leading from said battery to the thermostat A , and $I^2 I^3$ are conductors leading from said thermostat and connected, respectively, with the brushes $G G'$.

The thermostat, which I have indicated as a whole by the letter A , is, as herein shown, duplex, or provided with two separate and independently-operating thermostats $A' A^2$, attached to or contained in a single board or case. Each one of these thermostats $A' A^2$ is capable of independently operating the motor by completing an electric circuit through one or the other of the conductors $I^2 I^3$, and said thermostats are exactly alike, two of them being employed in connection with a switch for placing either one or the other in circuit with the battery and the electro-magnet which controls the motor, in order that one may be adjusted to move the valve or damper at one temperature and the other at another temperature, whereby the apparatus is adapted for maintaining an apartment or house at one temperature in the day-time and at another temperature at night, without other change than the shifting of the switch.

The thermostats $A' A^2$ are of familiar construction and contain in themselves no features of novelty. The parts of the two thermostats are lettered alike in the drawings, and a description of one applies to the other. Each of said thermostats embraces a supporting-post J , a spirally-coiled compound strip K , attached at its center to the post and provided with a radial metallic extension or arm k^2 at its outer end, and two contact-points $l l'$, supported by posts $L L'$ upon the case, said contact-points being arranged at opposite sides of the arm k^2 . The compound spiral strips K consist of two layers $k k'$, of materials which expand to different extent under the influence of heat, the materials used in the device shown being steel and hard rubber. Variations in temperature operate in a thermostat thus made to swing the arm k^2 into contact with one or the other of the contact-points $l l'$. The post J of the thermostat is connected with the battery-wire I' by conductors $i' i^2$, while the posts $L L'$, sustaining the contact-points $l l'$ of both thermostats, are connected, respectively, with the conductors $I^2 I^3$.

$M M'$ are two switches, which are preferably connected by an insulated cross-bar m , so that they will move together. The pivots of said switches are connected directly with the conductors $I^2 I^3$ by wires $i^3 i^4$, while the contact-points $m^3 m^4$, belonging to each switch, are connected with the posts $L L'$ of one thermostat, as A' , by wires $i^5 i^6$, and the contact-points $m^3 m^4$ are connected with the posts $L L'$ of the other thermostat, as A^2 , by wires $i^7 i^8$. The contact-points $l l'$ are so adjusted that when the temperature in the apartment in which the thermostat is placed is below that desired the end k^2 of the spiral coil K will rest in contact with the contact-point l , while as soon as the desired temperature is reached the end k^2 will be swung or moved by the action of the coil into contact with the contact-point l' . One pair of insulating-sections $c' c'$ of the distributor C^3 is so arranged

that when the damper D is closed the brush G will rest upon one or the other of said insulating-sections. The other pair of insulating-sections $c^2 c^2$ is so arranged that when the damper D is turned at right angles to its closed position to give the greatest opening to the pipe the brush G' will rest upon one of said sections $c^2 c^2$. The brush G is connected by the conductor I² with the contact-point l, as may be traced by the full and dotted lines in the drawings. The brush G' is similarly connected by means of the conductor I³ with the contact-point l'. When the temperature in the room is below the point desired, and the end k² of the thermostat is in contact with the point l, a circuit (broken at one point) may be traced from the battery through the conductor I', the thermostat-coil K, the contact-point l, the switch M, the conductor I², the brush G, the metal body of the commutator and the frame of the motor, the conductor i, the coil of the magnet H, and the conductor I back to the battery. At such time, however, the damper D is shut and the brush G rests upon the insulating-section c', as illustrated in the drawings, the circuit above traced being broken by the said insulating-section.

It is of course understood that in the particular arrangement of the parts herein shown for controlling the draft through the stove, the most intense heat is produced when the damper is closed.

When the desired temperature in the room is reached, it becomes necessary to open the damper D to check the draft through the stove, and this is accomplished when the parts are in the position shown in the drawings, and above described, as follows: As soon as the temperature is exceeded for which the thermostat (which is in circuit) is set the arm k² thereof swings into contact with the contact-point l'. A circuit is thereby established from the battery through the conductor I', the coil and thermostat, the contact-point l', the conductor I³, the brush G', the body of the commutator, (in contact with which the said brush G' at this time rests,) the conductor i, the coil of the electric magnet H, and the conductor I to the battery. As soon as this circuit is established, the core of the electromagnet will be energized, the armature H' will be attracted, the detent h' lifted, the regulating-fan released, and the motor will begin to turn and thereby give rotary movement to the damper D. The motor will continue to turn and move the damper as long as the brush G' rests in contact with the metal part of the distributor and until the said brush G' encounters and is lifted free from the body of the distributor by one of the insulating-sections c². These sections c² being arranged at an angular distance of a quarter of a circle from the insulating-sections c', the brush G' will remain in contact with the metal part of the distributor during one-fourth of the revolution of the shaft C' and

the damper D. The motion of the clock-work is interrupted as soon as the insulating-section c² is brought beneath the brush G' 70 by the breaking of the current and the dropping of the detent h' into engagement with the regulating-fan.

After the damper has been opened, as above stated, the parts will remain in the same position with both branches of the battery-circuit interrupted or broken until the temperature of the apartment falls below the point for which the thermostat is adjusted, when the arm k² of the thermostat will swing 80 into contact with the contact-point l and a circuit will be completed through the said contact-point, the conductor I², the brush G, and the electro-magnet thereby allowing the shaft C' to make another quarter-turn to close 85 the air-inlet-pipe.

It will of course be understood that the motor arranged and operating as described may be connected with and constructed to turn a valve or damper in any desirable or convenient manner—as, for instance, the valve or damper may operate to check or increase the heat given out by the heating apparatus either by being opened or closed, and the valve may be employed to control the smoke-pipe of a stove or furnace or the draft-aperture thereof, a duct supplying warm air to the apartment, a steam-heating pipe, the shutter of a ventilating-aperture, or other movable part or valve the moving of which influences the temperature in an apartment or building.

When two thermostats A' A² are employed, as herein shown, one of the thermostats will be commonly set to operate at a lower temperature than the other one—as, for instance, one will be set to operate at 70° for use in the day-time and the other at 60° to maintain that degree of temperature at night. The great advantage gained by the employment of two separately-adjusted thermostats is that no change or shifting of the parts of the thermostat itself is required for the purpose of varying the heat in the house or apartment, as necessary at different times. 115 Such adjustment of thermostats as heretofore made has rendered necessarily complicated and expensive construction therein, while the shifting devices employed have tended in their daily operation to change the 120 adjustment of the contact-points or other parts and thereby make the operation of the thermostat unreliable and inaccurate.

In a device embracing two thermostats and the switch for throwing either one into circuit, such as is herein shown, the thermostats themselves remain untouched after being once placed in adjustment, and the shifting of the switch is the only act required to produce the necessary variation in the temperature of the apartment, while the day and night temperatures remain unchanged.

The switch M need not be located upon the case of the thermostat, as shown, but it may

be located at a distance therefrom and in a place convenient for its actuation at the time it is required to move it—as, for instance, the switch or switches controlling the circuits of a thermostat or thermostats in one or more rooms may be located in a bed-room. The switch, furthermore, may be actuated automatically at desired times by a clock or time mechanism.

10 It is of course to be understood that in carrying out my invention the employment of the particular thermostat shown is not essential, and that any well-known or preferred form of thermostat may be employed, as found convenient or desirable.

15 As a further and separate improvement in temperature-regulating apparatus, I place the thermostat thereof in a box or casing O. The top and bottom walls are provided with openings or passages o o, allowing the free circulation of air through the casing and around the thermostat. The presence of the inclosing-casing O protects the thermostats from direct radiation, while at the same time, by 20 means of the apertures o o, allow ample access of the air of the room thereto. The employment of a casing or covering is of special importance in a room containing a stove or steam-radiator, inasmuch as the action of radiated heat is liable to operate the thermostat at the time when the air in the room is below the desired temperature. The casing is desirably provided with a removable front wall or cover O'. Upon the shaft C', 25 by which the damper is actuated, is desirably placed an index-hand or indicator P, attached to said shaft outside of the tube or pipe. The hand P turns with the shaft, and thereby serves to indicate to the eye at all times the 30 position of the valve or damper. When the indicator thus made shows the damper to be closed or open when it is obvious from inspection of a thermometer in the room that it should be otherwise, an indication is afforded that the motor is not wound or in running order, that the battery is exhausted, or 35 that for some other reason the apparatus is inoperative.

40 As shown in Figs. 3 and 5, the casing of the motor C is attached to the smoke-pipe by means of cylindric walls Q Q, forming a continuation of the cylindric side walls of the motor-ease and fitting at their inner edges against the pipe E.

45 The damper shown in Fig. 2 embraces a construction especially adapted for use in the case of dampers controlled by the heat-regulating devices. As shown in said figure, R is a ring of leather, cloth, or other flexible material secured to the margins of the damper and extending outwardly beyond the same, so as to bear against the inner surface of the pipe within which the damper is placed. As herein shown, the body of the damper consists of a flat plate, to the margins of which the flexible ring R is secured by means of a separate metal ring R', the parts being se-

cured together by rivets, as shown, or otherwise. In dampers heretofore made the margin of the damper seldom fits the interior of the pipe with sufficient closeness to completely shut off the passage of air through the pipe. The presence of the flexible ring, however, enables the pipe to be perfectly closed, thereby enabling the passage to be controlled with much more certainty and with less frictional resistance than would be present in the use of a damper fitted closely to the pipe and having no such flexible ring, whereby more perfect results in heat regulation are obtained than would otherwise be the case.

50 I have herein shown as located in the pipe E, between the damper D of the smoke-pipe F, a damper E', which may be actuated by hand for controlling the influx of air to the smoke-pipe independently of the heat-regulating devices. Said damper E' is useful for controlling the stove-draft independently of the regulating apparatus in starting the fire or at other times. Said damper is especially 55 useful when the draft of the chimney is not sufficient to carry off all of the air which enters the air-pipe E and at the same time maintain a draft through the stove sufficient to remove all the gas generated therein. The 60 said damper, in case of a weak or insufficient draft, will be partially closed, thereby partially cutting off the influx of cold air through the said air-pipe and thus causing a sufficient draft through the stove to carry away all the 65 gas generated therein and preventing its exit through the door or joints of the stove into the room.

65 I have hereinbefore described the armature II' as being arranged to gravitate away from the pole of the magnet. As one desirable way of constructing the armature to attain this end, I locate the pivot h thereof at the side of the metal block composing the armature nearest the polar surface of the magnet, so that the center of gravity of the block is exterior to its pivotal axis. A convenient and economical way of attaching the pivot-rod h to the armature is herein shown, and illustrated in Figs. 8 and 9. As shown in said figures, 70 the armature is provided in its side face nearest the magnet, near its lower margin, with a horizontal groove h², within which the rod for forming the pivot is inserted and secured by swaging, solder, or otherwise. I have found that the armature is rendered much more sensitive and more easily moved by making it of wedge shape, as shown, with its opposite side faces tapering upwardly. By this construction a heavy lower part is formed upon 75 the armature, located at one side of the pivot and tending to draw the upper end of the armature away from the magnet, while at the same time the upper part of the armature does not overhang the lower part when the armature is free from the magnet, so that the latter may be moved by a very slight or weak current.

80 I prefer to make the arms II² II³ as light as

possible, and by using such light arms upon an armature and in the manner described I am enabled to operate the device by the use of one battery-cell, whereas other similar devices as heretofore made have required two or more.

Certain features of construction in the smoke and air inlet pipes, dampers, means for attaching the motor to the pipe, and other features of construction herein illustrated are shown and claimed in a separate application for patent, Serial No. 272,387, filed by me in the United States Patent Office upon the 30th day of April, 1888.

15 The cylindric commutator or distributor C³ is secured to the shaft C' by means of a smooth cylindric hole in the commutator, into which the shaft is tightly fitted, as clearly shown in the drawings. The commutator is thus held 20 from turning upon the shaft solely by frictional engagement with the same, while the frictional resistance is not so great as to prevent the commutator being turned upon the shaft when considerable force is applied for 25 the purpose. This means of attaching the commutator to the shaft enables the commutator to be rotated for the purpose of adjusting the insulating-sections of the commutator with reference to the damper as necessary in originally assembling the parts of the apparatus 30 or for after adjustment of the same.

I claim as my invention—

1. A temperature-regulating apparatus comprising a valve, a valve-actuating device controlled by electricity, two separate thermostats adapted to operate at different temperatures, and a switch whereby either of said thermostats may be thrown into circuit with the valve-actuating device and the other excluded 40 from it, substantially as described.

2. A temperature-regulating apparatus comprising a valve, a thermostat, a motor embracing a clock mechanism, an electro-magnet in circuit with the thermostat, and a pivoted armature constructed to fall away from the magnet by gravity, said armature being provided with a detent-arm engaging a revolving part of the clock-work and being 45

pivotedly supported by means of a pivot-rod secured to the armature by being inserted in 50 a groove in one side of the metal block comprising the armature, substantially as described.

3. A temperature-regulating apparatus comprising a valve, a clock mechanism for actuating the valve, an electro-magnet, an armature provided with a detent engaging a revolving part of the clock mechanism, a thermostat having two contact-points, a commutator actuated by the clock mechanism, 55 brushes acting therein, two conductors leading from the opposite contact-points of the thermostat to the brushes, a third conductor leading from the body of the thermostat to the body of the commutator and embracing the 60 coils of the electro-magnet, and a battery in circuit with said conductors, substantially as described.

4. A temperature-regulating apparatus comprising a valve, a thermostat having two contact-points, a revolving shaft supporting and actuating the valve, a clock mechanism actuating said shaft, a cylindric commutator mounted upon the shaft and provided with two sets of insulating-sections located at opposite sides of a central line drawn around the cylindric surface of the commutator, the sections of one set being disposed at intermediate angular positions with reference to those on the other set, two brushes bearing 70 against said commutator, conductors leading from the contact-points of the thermostat to the said brushes, a third conductor leading from the body of the commutator to the body of the thermostat, and an electro-magnet in 75 circuit with the thermostat, commutators, and brushes, and an armature therefor provided with a detent which engages a moving part of the motor, substantially as described.

In testimony that I claim the foregoing as 80 my invention I affix my signature in presence of two witnesses.

DAVID W. THOMPSON.
